FLOOR CONSTRUCTION

Clarence E. Hovey, Kansas City, Mo., assignor to
 Gustin-Bacon Manufacturing Co., Kansas City,
 Mo., a corporation

Application February 28, 1938, Serial No. 193,106

5 Claims. (Cl. 189—35)

This invention relates to floor construction and particular means for maintaining the floor boards of railway cars in place upon the car sills, and the primary object is to provide a specially constructed clip for securing the floor boards in place.

One of the important aims of the instant invention is to provide a clip for floor construction of the aforementioned character, which clip is made of resilient sheet metal and formed in a special fashion so as to present a longitudinally arched body one end of which has an arcuate bearing face thereon for engaging the undersurface of the floor board along a line extending transversely across the floor clip, which line of contact changes as the nut on the retaining bolt of the structure is tightened.

Another important object of the invention is to provide a resilient floor clip of the nature specified, which clip engages the floor board and sill of the floor structure in such fashion as to hold the intermediate portion thereof an appreciable distance away from the underlying portions of the floor board and sill so that as normal expansion and contraction of the parts with which the clip is employed, takes place, its resilient capacity will be sufficient to compensate for the change, yet strong enough to maintain the floor board and sill in place.

A yet further aim of the invention is to provide a clip for floor construction which has a specially longitudinally arched body, the intermediate portion whereof, is perforated to receive an anchoring bolt and which portion arches inwardly as the nut of the anchoring bolt is tightened—all to the end that the straight edges of the nut have line contact with the outer surface of the clip body when the said straight edges of the nut are moved to transverse positions on either side of the anchoring bolt.

Heretofore, clips for car floor constructions have been provided with means for penetrating the floor board so that as the board shrinks or expands, due to climatic conditions, the clip will become loosened to a condition where it will jar out of the operative position. Such aforesaid types of clips therefore, have a destructive effect upon the floor boards and when the common practice of reversing the same is brought into play, the surface of the board originally engaged by the clip is objectionably torn and marred.

It has been found that a floor clip which has been so treated so as to be resilient or in the nature of an exceptionally strong, short, arcuate spring, need not be provided with means for ob-

jectionably piercing the floor board and further need not be equipped with separate units for precluding the accidental rotation of the securing nut which is carried by the anchoring bolt.

The preferred form of floor construction wherein is included the specially made clip is illustrated in the accompanying drawing, wherein,

Fig. 1 is a fragmentary sectional view through a portion of a railway car floor showing a clip made in accordance with the present invention.

Fig. 2 is a fragmentary sectional view taken on line II—II of Fig. 1.

Fig. 3 is a similar fragmentary detailed sectional view taken on line III—III of Fig. 1.

Fig. 4 is an enlarged fragmentary sectional view taken on line IV—IV of Fig. 3; and,

Fig. 5 is a perspective view of the clip member per se showing the same entirely removed from association with the remaining parts of the floor structure.

It is customary in floor constructions of the nature with which the specially created clip is to be used, to rest the floor boards 8 upon the horizontally extending flange 10 of sill 12 and to secure said boards 8 in such position through the medium of clip 14 which spans or bridges the joint between board 8 and flange 10 respectively, as shown in Fig. 1 of the drawing.

A threaded bolt 16 passes through board 8 so that a length thereof depends therebelow and so that the longitudinal axis thereof is spaced outwardly from the edge of flange 10 approximately one inch.

Clip 14 is longitudinally arched so that in its original form it appears substantially as illustrated in Fig. 5. Clip 14 is provided with a perforation 18 which has its axis on the longitudinal axis of clip 14. This perforation 18 is through the intermediate portion of clip 14 and midway between the ends. Perforation 18 is elongated and its major axis is on the longitudinal axis of clip 14 so that as the intermediate portion of the clip is arched inwardly, the sides of perforation 18 will not grip bolt 16.

The end of clip 14 which engages the underside of board 8 is formed to present an arcuate bearing face 20. The undersurface of board 8 is always at a tangent to the said arcuate face and therefore, a line contact between this end of clip 14 and board 8 extends transversely across the clip at different points, as the body of clip 14 is flexed during the tightening of nut 22. The other end of clip 14 bears directly against the underside of flange 10 formed on sill 12 and when

the ends of clip 14 are positioned as shown in Fig. 1 of the drawing, the intermediate portion thereof is an appreciable distance from the underlying parts of board 8 and flange 10 respectively.

- 5 When nut 22 is tightened, the straight edges 24 thereof come into line contact with the outer face of clip 14 on transverse lines between bolt 16 and the ends of clip 14. These straight edges 24 therefore, with the concave outer face of inwardly arched portion 26 of clip 14, create a relation of parts which tend to lock nut 22 against rotation. It is necessary to exert a force upon nut 22 that is great enough to further flex the resilient body of clip 14 before nut 22 can be 10 turned upon bolt 16. Obviously, it is desirable to use a square nut 22, which presents opposite straight edges 24 so that the diagonal distance across the inner face of nut 22 will be great enough to prove a substantial barrier to the 15 accidental turning of nut 22.

The placement of perforation 18 on the medial transverse line of clip 14 insures that tightening nut 22 will create an inwardly arched portion 26 as and for the purpose contemplated. In securing clip 14 in place, its form changes from that shown in dotted lines of Fig. 1 to that shown in full lines in said figure. The position shown in full lines is at normal gripping position and the resilient property of the clip when in such position 20 insures that a holding force will always be exerted within the extreme limits of expansion and contraction of either floor board 8, sill and flange 10 and 12, or bolt 16. The body of clip 14 when so held intermediate its ends will "follow" the undersurfaces of flange 10 and board 8 and the parts will thereby be held in assembled relation until bolt 22 is purposely loosened.

Clip 14 is made of $\frac{3}{16}$ inch stock which is heat treated in the conventional type electric furnace 40 and then quenched in the usual fashion, to establish the desired amount of resiliency. The length of clip 14 from end to end is substantially 4 $\frac{1}{4}$ inches and its width should be about 1 $\frac{1}{2}$ inches. The shorter diameter of perforation 18 is but a few thousandths greater than the diameter of the $\frac{1}{2}$ inch bolt so that any danger of accidental transverse tipping during placement of the clip is overcome. The use of clips 14 which have been purposely made resilient and that have 45 a greater portion intermediate their ends, spaced from the underlying surfaces of board and sill flange are found to be highly desirable and when one such clip is used to hold each floor board 8 in place against the underlying sill, there can be 50 no accidental loosening and therefore objectionable displacement.

It has been found desirable to form detents 28 on the side of clip 14 next to nut 22. These detents are small dome-shaped, integral members 60 disposed beside the opposed edges 24 of nut 22 so that they present a further barrier against the accidental turning of said nut 22.

Detents 28 may be formed prior to heat treating clip 14 by forcing small areas of the clip outwardly 65 at points close to the edges of nut 22. The height of detents 28 is not great enough to hold nut 22 against movement when the clip is being applied as the nut is turned to loosen its hold on the underside of clip 14.

When intermediate portion 26 of clip 14 is inwardly arched, these detents 28 are actually on a concave portion, the fact of which is in line contact with edges 24.

70 75 Having thus described the invention, what is

claimed as new and desired to be secured by Letters Patent is:

1. In a floor construction having a flanged sill and a floor board supported thereby, the combination of a perforated, longitudinally arched clip 5 formed of resilient sheet metal, said clip having its inner face at one end bearing against the floor board and its inner face at the other end bearing against the flange of said sill; a screw threaded bolt anchored in the floor board and extending through the perforation; and a nut threaded onto the bolt against the outer face of the clip substantially midway between the ends of said clip, that portion of the clip intermediate its ends being spaced an appreciable distance from the underlying portion of the flange and floor board when the nut is tightened to secure the latter together, the resilient property of said clip being such as to permit normal expansion and contraction of the sill, the floor board and the bolt as all 10 15 20 of the aforesaid parts are held together with sufficient force to preclude displacement.

2. In a floor construction having a flanged sill and a floor board supported thereby, the combination of a perforated, longitudinally arched clip 25 formed of resilient sheet metal, said clip having its inner face at one end bearing against the floor board and its inner face at the other end bearing against the flange of said sill; a screw threaded bolt anchored in the floor board and extending through the perforation; and a nut threaded onto the bolt against the outer face of the clip substantially midway between the ends of said clip, the intermediate portion of said clip being inwardly arched by the pressure exerted 30 35 thereon when said nut is tightened whereby the edges of said nut at its inner face are forced into line contact with the outer face of the clip along transverse lines between the ends of the clip and said nut.

3. In a floor construction having a flanged sill and a floor board supported thereby, the combination of a perforated, longitudinally arched clip 40 formed of resilient sheet metal, said clip having its inner face at one end bearing against the floor board and its inner face at the other end bearing against the flange of said sill; a screw threaded bolt anchored in the floor board and extending through the perforation, substantially midway between the ends of said clip; and a nut threaded onto the bolt against the outer face of the clip, the intermediate portion of said clip opposed to said nut being inwardly arched by the pressure exerted thereon when said nut is tightened whereby when the nut is disposed with one straight edge thereof on a line extending transversely of the clip, a line contact between the outer face of the clip and the straight edge of the nut is established for the purpose specified.

4. In a floor construction having a flanged sill 60 and a floor board supported thereby, the combination of a perforated, longitudinally arched clip formed of resilient sheet metal, said clip having its inner face at one end bearing against the floor board and its inner face at the other end bearing 65 against the flange of said sill; a screw threaded bolt anchored in the floor board and extending through the perforation, substantially midway between the ends of said clip; and a nut threaded onto the bolt against the outer face of the clip, the intermediate portion of said clip opposed to said nut being inwardly arched by the pressure exerted thereon when said nut is tightened whereby when the nut is disposed with one straight edge thereof on a line extending transversely of the 70 75 80 85 90 95

clip, a line contact between the outer face of the clip and the straight edge of the nut is established for the purpose specified, the perforation through said clip being elongated with its major axis extending longitudinally of the clip, the transverse diameter of said perforation being substantially the same as the diameter of the said bolt.

5. In a floor construction having a flanged sill and a floor board supported thereby, the combination of a perforated, longitudinally arched clip formed of resilient sheet metal, said clip having its inner face at one end bearing against the floor board and its inner face at the other end bearing

against the flange of said sill; a screw threaded bolt anchored in the floor board and extending through the perforation, substantially midway between the ends of said clip; and a nut threaded onto the bolt against the outer face of the clip, the intermediate portion of said clip opposed to said nut being inwardly arched by the pressure exerted thereon when said nut is tightened, said clip having a plurality of detents formed on the inwardly arched, intermediate portion of said clip 10 adjacent to the edges of said nut when the latter is in the operative position.
